(57) **CLAIM**

The ornamental design for a load testing linkage member as shown and described.

DESCRIPTION

FIG. 1 depicts a front perspective view of the load testing linkage member of the present invention.

FIG. 2 depicts a first side elevation view of the load testing linkage member depicted in FIG. 1.

FIG. 3 depicts a top view of the load testing linkage member depicted in FIGS. 1 and 2.

FIG. 4 depicts a bottom view of the load testing linkage member depicted in FIGS. 1 through 3.

FIG. 5 depicts an end view of the load testing linkage member depicted in FIGS. 1 through 4; and,

FIG. 6 depicts a sectional view of the load testing linkage member depicted in FIGS. 1 through 5, along line 6-6 depicted in FIG. 2.
